(57) **CLAIM**

The ornamental design for corner post assembly for a container, as shown and described.

DESCRIPTION

FIG. 1 is an exploded front perspective view of a corner post assembly showing our new design;

FIG. 2 is an exploded front view thereof;

FIG. 3 is an exploded side view thereof, the adjacent side view being a mirror image thereof;

FIG. 4 is an exploded rear view thereof;

FIG. 5 is an assembled side perspective view thereof;

FIG. 6 is a top plan view thereof;

FIG. 7 is a bottom plan view thereof; and,

FIG. 8 is a side perspective view thereof in association with environmental materials shown in broken lines.

Environmental material is shown in broken lines and forms no part of the design.
